UNITED STATES PATENT OFFICE.

BERNHARD GENTRUP, OF HALLE-ON-THE-SAALE, GERMANY.

DAMPER FOR FLUES AND THE LIKE.

1,413,469.

Specification of Letters Patent. Patented Apr. 18, 1922.

Application filed September 2, 1921. Serial No. 498,091.

To all whom it may concern:

Be it known that I, BERNHARD GENTRUP, a citizen of the German Republic, and residing at Halle-on-the-Saale, Germany, have 5 invented certain new and useful Improvements in a Damper for Flues and the like, (for which I have filed applications in Germany August 21, 1916, Design Patent No. 651,938, and also in Germany March 5, 1918, 10 Design Patent No. 681,178,) of which the following is a specification.

This invention relates to a flue damper constructed in the manner of Venetian blinds and intended for controlling the passage of smoke or the like through flues or conduits or the like. The flue consists of a plurality of parallel plates or strips, each of which has a pivot at each of its short edges, and the pivots lie in oblong holes provided 15 in profiled iron rails located the one at the one side, the other at the other side of that plurality of plates or strips. The oblong holes lie horizontal and the pivots roll upon the lower edges of said holes, that is to say: 20 they do not rotate as in circular holes.

There arises, thus, only rolling friction, but not sliding one, whereby the adjustability of the damper is greatly improved.

Adjusting the plates or strips is effected 30 by a draw-rod which is connected with the plates or strips by links movably connected with the said plates or strips, as well as with the said rod, and the adjustment is effected by lifting or lowering that rod. An important feature concerning this rod is that 35 it is subdivided into two parts, of which the one is located at the one side of the damper and the other at the other side of the damper, in such a manner, that the weights of the two 40 parts balance each other either completely or at least approximately, which also contributes to an easy actuation of the damper.

In order to make my invention more clear, I refer to the accompanying drawing, in 45 which Figure 1 is a front view of the damper and shows it in closed state; Figure 2 is a side view of the damper showing it in open state; Figure 3 is a plan, the position of the plates or strips (of which only one is to be seen) corresponding to Figure 1; and Figure 50 4 shows in its left part a portion of one of the side rails on a larger scale and seen from the inner side, and in its right part a vertical section through this rail portion.

55 Each of the parallel plates or strips *a* is provided with two pivots *b*, and each pivot

is supported in a horizontal oblong hole *c* of the parallel vertical side rails *d*. The pivots may thus roll in the holes from the left to the right, and reversely, whereby the friction 60 is greatly reduced, compared with pivots turning in circular holes, in which gliding friction arises.

Opening and closing the plates or strips *a* is effected by a rod *f*, which is subdivided 65 into two parts, of which the one is located in front of the plates and the other at their rear. The two rod parts *f* are connected with the plates *a* by links *g*. One of the plates has a link *g* at its front, as well as its 70 rear, whereby the weight of the two rod parts is practically balanced and the resistance to motion is either completely compensated or rendered at least approximately constant.

Having now described my invention, what I desire to secure by a patent of the United States is:

1. A damper for flues, conduits, and the like, comprising, in combination: a set of 80 parallel damping elements, lateral pivots at said elements; horizontal oblong holes provided in said supports and being engaged by said pivots; and means for operating the said elements. 85

2. A damper for flues, conduits, and the like, comprising, in combination: a set of parallel damping elements; lateral pivots at said elements; lateral supports for the elements; horizontal oblong holes provided in 90 said supports and being engaged by said supports; and operating means hinged to the said elements, substantially as described.

3. A damper for flues, conduits, and the like, comprising, in combination: a set of 95 parallel damping elements; lateral pivots at said elements; lateral supports for the elements, horizontal oblong holes provided in said supports and being engaged by said supports; links hinged to the said elements, and 100 rods connected with said links, for the purpose set forth.

4. A damper for flues, conduits, and the like, comprising, in combination: a set of parallel damping elements; lateral pivots at 105 said elements; lateral supports for the elements; horizontal oblong holes provided in said supports and being engaged by said supports; links hinged to the elements; and a bipartite rod, of which the one part is connected with said links on the one side of the 110 said elements, and the other part is con-

nnected with said links on the other side of the said elements, substantially and for the purpose as described.

5. A damper for flues, conduits, and the like, comprising, in combination: a set of parallel plates; a pivot at the short edge of each plate; two vertical lateral supports for said plates; horizontal oblong holes provided in the supports and being engaged by the pivots; a set of links attached to a part of the said plates on the one side, and a set of links attached to a part of the said plates on the other side of the set; and rods connected with said links and being adapted to 10 actuate the plates by the mediation of the said links, substantially as described.

6. A damper for flues, conduits, and the like, comprising, in combination: a plural-

ity of horizontal parallel strips; lateral pivots attached to said strips; lateral supports 20 having horizontal oblong holes situated at said pivots and being in operative engagement with them; vertical rods located the one at the front, the other at the rear of the set of strips; and hinges connecting some of 25 the said strips with one of the said bars and some of the said strips with the other of said bars, substantially and for the purpose as described.

In testimony whereof I have affixed my 30 signature in presence of two witnesses.

BERNHARD GENTRUP.
